Patented June 30, 1925.

UNITED STATES PATENT OFFICE.

JOHN B. ARPIN, OF WISCONSIN RAPIDS, WISCONSIN.

PLANT FOR SEPARATING COKE.

Application filed July 28, 1922. Serial No. 578,068.

To all whom it may concern:

Be it known that I, JOHN B. ARPIN, a citizen of the United States, and a resident of Wisconsin Rapids, in the county of Wood 5 and State of Wisconsin, have invented certain new and useful Improvements in a Plant for Separating Coke; and I do hereby declare that the following is a full, clear, and exact description of the same, reference 10 being had to the accompanying drawings, and to the numerals of reference marked thereon, which form a part of this specification.

This invention relates to apparatus for 15 recovering coke from ashes.

It is an object of this invention to provide a plant for this work which shall not require the presence of a stream of flowing water, but may be used on the shore of 20 standing water, or at sea.

It is a further object of this invention to provide a means for rapidly and inexpensively separating coke from ashes whereby either the coke, the clinker or the ashes may 25 be handled directly from railway cars.

It is a further object of this invention to provide a means for nice adjustment of the apparatus to care for changes in conditions or in the character of the ashes even when 30 such adjustment requires the movement of a large weight of ashes.

Other and further important objects of this invention will be apparent from the disclosures in the accompanying drawings and 35 specification.

The invention (in a preferred form) is illustrated in the drawings and hereinafter more fully described.

On the drawings:

40 Figure 1 is a top plan view of the plant.
Figure 2 is a side view.

Figure 3 is an end view.

Figure 4 is a section upon the line 4—4 of Figure 1.

45 Figure 5 is a section upon the line 5—5 of Figure 1.

Figure 6 is a top plan view of the parts shown at the left of Figure 4.

50 Figure 7 is a section upon the line 7—7 of Figure 1.

Figure 8 is a section upon the line 8—8 of Figure 3.

55 Figure 9 is an enlarged view partly in section of a detail showing the scraper associated with the belt at the left hand part of Figure 1.

As shown on the drawings:

A railway track 10 is provided by which ashes may be brought to or coke or clinkers carried away from the plant. Besides the 60 track 10 are bins 11 for the reception of ashes. The ashes from these bins descend upon two conveyor belts 12, shown in Figure 8. These belts are driven in any convenient manner so that they run from the 65 two ends of the row of bins toward the center. In the form illustrated, they are driven by a pair of gear wheels 13, which receive their power from a sprocket chain which leads to any suitable source of power. 70 The conveyor belts deliver into a chute 15 which leads the ashes to a rotating sieve 16 driven by a sprocket chain 17 receiving its power from the shaft of one of the rollers 75 13. The rotating sieve has an axis which is not horizontal but slopes slightly downward and away from the belts. The lower end of the sieve is located above a receiving funnel 20 which delivers into the pipe 21. This pipe leads from an elevated tank 80 23 which will be described below.

The delivery end of the pipe 21 is over a funnel-shaped car 24 which is supported upon a raft 25. The pipe 21, therefore, must be long enough to reach from the 85 structure near the tracks on the shore to a point beyond the shore where the water is deep enough for the operation described below. Upon the raft 25 are two rails, one of which 26 may be any ordinary type of 90 railroad rail. The other 27 is preferably in the form of a rack bar. The wheels of the car 24 are made to correspond, those illustrated in Figure 4, therefore, being cog 95 wheels for co-operation with the rack. One axle of the car is provided with a worm wheel 30 adapted to be driven by a screw 31 and by a hand wheel 32. By the rotation of the hand wheel 32, therefore, the position of the car upon the tracks 26 and 100 27 may be adjusted with great nicety.

The raft 25 is held in place by means of piles 40 or in any other desired manner. The raft is in the form of a frame surrounding a well. From one side of this well goes a mouth or funnel 41 leading to a pipe 42. The side of the well has an opening for the large end of the funnel 41. From the lower edge of this opening the wall of the well slopes downward and toward the center of the well forming a baffle plate 44 which leads material onto a conveyor 45 110

extending obliquely upward and through an opening in the other side of the well. This conveyor extends beyond the surface of the water to any convenient delivery point (not illustrated).

The funnel 41 is rectangular in cross section to extend across the whole of one side of the well. The opening in this side of the well is sufficient to permit the funnel a considerable vertical movement. This movement is provided for by a hoist including a cable 46. The A frame for this hoist extends from one side of the raft as shown at 47. By lifting or lowering with this hoist the height of the entrance edge of the mouth 41 may be varied. In order that no material may escape above the mouth 41, a plate 48 is provided secured below the water line to the same side of the raft as the hoist 47. The plate 48 is preferably made of two overlapping parts adjustably secured together in any way. The lower edge of the plate is thus made to contact with the upper side of the funnel.

From the funnel the pipe 42 leads to a pump 50 situated on the bank. The pump 50 delivers to a pipe 51 leading to the tank 23. From the pipe 51 the water is discharged against a screen 53, as best shown in Figure 5. The water passes through this screen and descends to the bottom of the tank 23 from whence it passes out through the pipe 21, as first described. The coke which traveled in pipes 42 and 51 with the water descends the screen 53 and is received upon a conveyor belt 55. The belt is not horizontal but travels up a gradual slope so that the coke thereon may have ample opportunity to drain.

At intervals along the belt scrapers 57 are located. As shown in Figure 9, these scrapers are mounted upon pivots 58 secured to the wall 59 which forms one side of a set of bins 60 situated below the tank 23 and over the track 10 and into which the conveyor belt 55 delivers. By lifting one of the scrapers, as shown in dotted lines in Figure 9, coke may be permitted to pass further along the belt and so delivered to a bin further from the tank 53, but by lowering the scrapers into operative position, the coke may be made to leave the belt at the first bin. The bins terminate in a series of mouths 61, each closed by a suitable gate 62 so that they will deliver only when the gate is opened, which will be done when a railroad car is situated beneath the bin.

In the operation of the device, the ashes is placed in the bins 11 by any suitable unloading mechanism from the railroad cars. It descends these bins and arrives on the conveyor belts 12 which deliver it to the chute 15, from whence it passes through the rotating sieve 16. The finer part of the

ashes passes through the meshes of this

sieve; the coarser part travels the length of the sieve and is delivered into the funnel 20 and so introduced into the pipe 21. The stream of water flowing through this pipe carries the ashes through it to the car 24. 70 The funnel shape of this car causes the ashes to be delivered in a sheet as wide as the well permits and no thicker than the width of the mouth of the funnel 24. The action of the pump 50, by creating a current through 75 the mouth 41, draws the coke into this mouth, but the clinker or other heavy parts of the ashes pass below the mouth, and, striking the baffle plate 44, descend to the conveyor 45 which carries them to the selected delivery point.

The height of the mouth of the funnel 24 above the lower edge of the mouth 41 should be great enough to permit the current to produce an ample separation between the 85 lighter coke and the heavier clinker. If possible, a place should be selected for the plant where the depth of the water is sufficient to permit this height to be at least six feet.

The division between the coke and the clinkers can be regulated by means of the hoist, the cable 46 raising or lowering the lower edge of the mouth 41. It may also be regulated by the wheel 32, moving the car 95 24 slightly toward or away from the mouth 41. The coke is moved into the mouth 41 by the current through the well. Once inside the mouth, the current is confined by the walls of the passage and the coke is 100 therefore moved with certainty. It passes through the pipe 52 and is sent by the pump 50 through the pipe 51 onto the screen 53. The water passes through this screen and down the pipe 21, thereby supplying ample 105 current to move the coke from the funnel 20 to the car 24. The coke from pipe 51 rolls down the screen 53, being largely separated from the water during this passage. It is then received upon the conveyor belt 110 55. A further drainage takes place during the passage of the coke on this conveyor. The coke is removed from this conveyor by one of the scrapers 57 and falls into one of the bins 60. When a car on the track 10 is 115 positioned under the mouth 61, the gate 62 will be opened and a supply of coke from the bin will descend into the car. The car will then transport the coke to the desired place.

If desired the screen 53 may be made to slope the other way so that the flow of water from the pipe 51 shall assist the motion of the coke down the screen. Also the parts of the apparatus shown as on shore may be 125 mounted on a scow or skiff or other vessel if it is desired to have the whole apparatus at sea.

I am aware that numerous details of construction may be varied through a wide 130

range without departing from the principles of this invention, and I therefore do not purpose limiting the patent granted otherwise than necessitated by the prior art.

5 I claim as my invention:

1. In a hydraulic apparatus for separating coke from ashes, a raft, a well beneath said raft permanently open at the bottom for free fall of the ashes therethrough, a 10 passage leading from said well, and suction means for creating a current through said passage.

2. In a device of the class described, a raft, a funnel mounted upon said raft, a 15 passage leading away from said raft, and means for adjusting the position of the funnel upon the raft toward or away from said passage.

3. In a device of the class described, apparatus for handling ashes and coke situated upon the shore, a raft situated upon a 20 body of standing water, connections between the two including a pipe line, a pump in said pipe line, a second pipe line, and 25 means for introducing ashes to said second pipe line.

4. In a device of the class described, a raft, a hoist upon said raft, a conduit supported by said hoist whereby the height of 30 the conduit relative to the raft may be adjusted, an apron extending from said raft to said conduit, means for delivering from the raft into the water a mixture of materials, and means for creating suction 35 through said conduit for removing the lighter of said materials.

5. In a device of the class described, a 40 tank, a pipe delivering a mixture of coke and water to said tank, means within the tank for separating the coke from the water, and a conveyor for removing the separated coke from said tank, a row of bins adjacent to said tank, scrapers pivotally se-

cured to said bins whereby the scrapers may be positioned to remove coke from said conveyor or to permit the coke to remain on the conveyor so that the conveyor leads the coke to the selected bin.

6. In a device of the class described, a circulating system, a pump for delivering a stream of water through said system, said system including a body of standing water, a pipe from said body to said pump, a second pipe from said pump to an elevated tank, the said elevated tank for separating coke from the water, a pipe from said elevated tank to a point above the body of standing water, means for introducing ashes into the water during its circuit through said pipe, and means in the body of standing water for separating coke from ashes.

7. In a device of the class described, a raft, a pair of rails upon said raft; one of said rails being in the form of a rack bar, a carriage running on said rails, some of the wheels on said carriage being toothed to cooperate with said rack bar, and a slow-motion hand-driven device for rotating said wheels whereby the position of the carriage 50 may be positioned lengthwise of said rails.

8. In a device of the class described, a raft, a well in the middle of said raft, suction means at one side of said well, a device above said well for delivering a mixture of material, means for adjusting the height of said suction means, and means for adjusting the horizontal position of said delivery means.

In testimony whereof I have hereunto 60 subscribed my name in the presence of two subscribing witnesses.
